MARKING IMPLEMENT

William E. Krueger and Hugh M. Hodge,
Detroit, Mich.

Application June 18, 1931, Serial No. 545,234

4 Claims. (Cl. 91—62.6)

The present invention relates in general to improvements in devices for marking or decorating objects with colored lineations, and relates more specifically to improvements in the construction and operation of marking implements especially adapted to apply lines or stripes of paint to objects such as automobile bodies, boxes or the like.

An object of the invention is to provide an improved marking implement which is simple and compact in construction, and which is highly efficient in operation.

Another object of the invention is to provide an improved fountain-brush or the like, wherein the liquid is gradually and effectively delivered from the source of supply to a nozzle or other point of utilization.

A further object of the invention is to provide an improved marking or striping device which may be manipulated in a manner similar to an ordinary pen or pencil, to apply paint lines or stripes to objects.

Still another object of the invention is to provide an improved painting tool wherein the delivery of paint may be readily and accurately controlled, and which is adapted to produce lines of any desired thickness and of uniform width.

Another object of the invention is to provide an improved painting implement which may be conveniently cleaned, refilled, and otherwise maintained in operative condition and ready for use.

A further object of the invention is to provide a marking device for applying liquid, which has large liquid capacity, and which may moreover be manufactured at minimum cost.

These and other objects and advantages will be clearly apparent from the following detailed description.

A clear conception of several embodiments of the invention, and of the mode of constructing and of manipulating marking implements built in accordance therewith, may be had by referring to the drawings accompanying and forming a part of this specification in which like reference characters designate the same or similar parts in the various views:

Fig. 1 is an elevation of one form of the improved implement, looking toward the liquid flow control lever and toward the end of the liquid

supply reservoir;

Fig. 2 is a central longitudinal section through the implement and supply reservoir of Fig. 1, the section being taken along the line 2—2 of Fig. 1;

Fig. 3 is an enlarged longitudinal section through the flow control portion of the imple-

ment, taken at right angles to the section of Fig. 2 and showing the control valve closed;

Fig. 4 is a similarly enlarged longitudinal section through the flow control portion of the implement, taken the same as in Fig. 3 but showing the control valve fully opened; and

Fig. 5 is a central longitudinal section through a modified form of implement and liquid supply reservoir.

Referring specifically to the embodiment of the invention shown in Figs. 1 to 4 inclusive, the improved implement comprises in general a marker support 10, a brush or nozzle 11 detachably associated with one end of the support, a reservoir 12 formed integral with the opposite end of the support, and a plunger 13 for forcing liquid such as paint 14 from within the reservoir 12 through the support 10 to the nozzle 11.

The support 10 is provided with a longitudinal passage 15 the opposite ends of which are in open communication with the nozzle 11 and reservoir 12, and a rotary plug valve 16 coacting with a tapered transverse seating in the support 10, intercepts the medial portion of the passage 15 and is adapted to control the flow of liquid therethrough. The valve 16 is maintained against its tapered seating by means of a resilient packing 17 and a removable retainer plug 18, and a manipulating lever 19 is secured to the stem of the valve 16 by a nut 20. The support 10 is moreover provided with a fixed abutment 21 for limiting the closing movement of the lever 19, and a set screw 22 cooperating with a lug 23 formed integral with the support 10, serves to vary the limits of the opening movement of the lever 19. A coil spring 24 embracing the point of the set screw 22 and reacting against the lug 23, constantly urges the lever 19 toward the stop abutment 21, and the degree of opening of the valve 16 may obviously be varied by merely adjusting the set screw 22.

The delivery device or nozzle 11 is detachably secured to the support 10 by means of a lock nut 25 coacting with the nozzle carrier 26 and with the end of the support, thus making it possible to substitute various types and sizes of nozzles or brushes. The liquid passages in these nozzles may be of various diameters, and are usually considerably smaller than the passage 15 in the support 10.

The end of the cylinder or reservoir 12 which communicates with the passage 15 of the support 10, may be provided with a removable closure 27 for filling the reservoir displacement chamber with liquid paint 14 or the like. The opposite end of the reservoir 12 is provided with a re-

95

100

105

110

movable cap 28 through which the plunger rod 29 extends, and a helical-spiral compression spring 30 surrounds the rod 29 and coacts with the cap 28 and plunger 13. The plunger 13 is furthermore provided with a cup-shaped packing 31 which is held in place by a retainer 32 and nut 33, and prevents paint 14 from escaping past the plunger 13. When the reservoir 12 is being filled with paint 14, the plunger 13 is withdrawn by hand 10 with the aid of the rod 29, to compress the spring 30, and this spring 30 subsequently functions to urge the plunger 13 against the paint 14 confined within the reservoir, upon release of the rod 29. If the control valve 16 is then opened, the spring 15 30 coacting with the plunger 13 will force paint from the reservoir 12 through the passage 15 and nozzle 11 until the supply is entirely deleted or exhausted.

The mode of utilizing the implement shown in 20 Figs. 1 to 4 inclusive, should be clearly apparent from the foregoing description. When the reservoir 12 has been properly charged with paint 14 and the closure 27 has been applied, the implement may be manipulated like an ordinary pencil or brush to produce lines of paint flowing from the nozzle 11. A finger of the operator may be applied to the control lever 19 to regulate the flow of paint, and the set screw 22 serves to vary the degree of opening of the passage 15. As the 25 paint 14 is discharged from the reservoir 12 by the spring 30, the plunger 13 gradually approaches the closure 27 until the paint supply is entirely exhausted. The various parts may be readily removed for inspection and cleaning, by merely releasing the cap 28 and plug 18, and the implement is so compact that it can be carried in an ordinary pocket.

Referring specifically to the embodiment of the invention shown in Fig. 5, the implement again 30 comprises a support 40, a nozzle 11 secured to one end of the support by means of a carrier 26 and lock nut 25, a reservoir 42 connected to the opposite end of the support 40 by means of a hose 41, and a plunger 43 movable within the reservoir 42 by means of a helical-spiral spring 44. The support 40 differs from the support 10 previously described, only in that it is flexibly connected to the supply reservoir 42 by the hose 41, instead of being rigidly attached to the reservoir. The support 40 is provided with a control valve 16 identical with that previously described, and the nozzle 11 and its attachment are also the same as those heretofore described.

The upper cap 45 of the receiver 42 is provided 35 with an eye 46 for suspending the same from the belt of an operator or from a trolley, and this cap 45 is moreover provided with a closure 27 for supplying paint 14 to the reservoir 42. The lower cap 47 against which the spring 44 reacts, has a central bushing 48 with which the hollow plunger rod 49 coacts. The plunger 43 as in the case previously described, is provided with a cup-shaped packing 31 held in place by a retainer 32 and a nut 33, and the plunger rod 49 has a through 40 passage 50 therein, the upper end of which communicates with the paint supply confined within the reservoir 42, and the lower end of which communicates with the hose 41 through a nipple 51 attached to the lower end of the plunger 49.

The implement of Fig. 5 enables the storage of a greater supply of paint 14, than is possible with the pocket implement previously described, by virtue of the fact that a reservoir 42 of any desired capacity may be utilized. The hose 41 may be of any desired length and is sufficiently flexible so

as not to interfere with the free movement of the support 40 and nozzle 11 during normal use of the implement. In the implement of Fig. 5, the rate of flow of the paint 14 from the reservoir 42 will be substantially constant because of the vertical disposition of the reservoir, and as the paint supply is diminished, the spring 44 will expand and the difference in expansive effort of the spring as its limit of expansion is reached, will be compensated for by the diminishing weight of the paint supply. 80 85

From the foregoing description it will be apparent that the present improvement provides a marking implement which is extremely simple and compact in construction, which is highly efficient in operation, and all parts of which are readily accessible for cleaning. The delivery of paint from the supply reservoir may be readily and accurately controlled by manipulating the control lever 19 and by adjusting the set screw 22, and the nozzle 11 may be conveniently replaced by any other suitable type of nozzle or brush. The supply of paint 14 may be readily replenished with the aid of the plunger rod, and the spring coacting with the plunger effectively maintains the liquid hermetically sealed and in constant 100 105 readiness of use.

It should be understood that it is not desired to limit the invention to the exact details of construction herein shown and described, for various modifications within the scope of the claims may occur to persons skilled in the art.

It is claimed and desired to secure by Letters Patent:

1. A marking implement comprising, a liquid confining reservoir, a plunger movable in said reservoir and having a hollow plunger rod movable therewith and communicating with said reservoir, a marking nozzle having at one end a restricted but unobstructed delivery orifice, a flexible liquid conducting connection between the opposite end of said nozzle and said rod, a rotary valve associated with said nozzle closely adjacent to said orifice for controlling the passage of liquid from said reservoir to said nozzle, a manually operable lever for opening said valve, and an adjustable stop for limiting the valve opening movement of said lever. 110 115 120

2. A marking implement comprising, a liquid confining reservoir, a plunger movable in said reservoir and having a hollow plunger rod movable therewith and communicating with said reservoir, a marking nozzle having at one end a restricted but unobstructed delivery orifice, a flexible liquid conducting connection between the opposite end of said nozzle and said rod, a rotary 125 130 135 valve associated with said nozzle closely adjacent to said orifice for controlling the passage of liquid from said reservoir to said nozzle, and a manually operable lever for opening said valve.

3. A marking implement comprising, a liquid confining reservoir, a plunger movable in said reservoir and having an opening therethrough communicating with the interior of said reservoir, a marking nozzle having at one end a restricted but unobstructed delivery orifice, a flexible liquid 140 145 150 conducting connection between the opposite end of said nozzle and said plunger opening, a rotary valve associated with said nozzle closely adjacent to said orifice for controlling the passage of liquid from said reservoir to said nozzle, a manually operable lever for opening said valve, and an adjustable stop for limiting the valve opening movement of said lever.

4. A marking implement comprising, a liquid confining reservoir, a plunger movable in said 150

reservoir and having an opening therethrough communicating with the interior of said reservoir, a marking nozzle having at one end a restricted but unobstructed delivery orifice, a flexible liquid 5 conducting connection between the opposite end of said nozzle and said plunger opening, a rotary

valve associated with said nozzle closely adjacent to said orifice for controlling the passage of liquid from said reservoir to said nozzle, and a manually operable lever for opening said valve.
